UNITED STATES PATENT OFFICE.

JOSEPH B. RHODES, OF HARRISBURG, PENNSYLVANIA.

AUTOMATIC STOP-MOTION FOR KNITTING-MACHINES.

No. 894,698.

Specification of Letters Patent.

Patented July 28, 1908.

Application filed September 30, 1907. Serial No. 395,175.

To all whom it may concern:

Be it known that I, JOSEPH B. RHODES, a citizen of the United States, residing at Harrisburg, in the county of Dauphin and State of Pennsylvania, have invented certain new and useful Improvements in Automatic Stop-Motions for Knitting-Machines; and I do declare the following to be a full, clear, and exact description of the invention, such as will enable others skilled in the art to which it appertains to make and use the same.

This invention relates to improvements in yarn controllers for textile machinery, and relates more particularly to an automatic stop-motion for rib-knitting machines, and is especially designed as an improvement over the device for which Letters - Patent were granted May 7, 1907, Number 853,032.

20 The object of the invention is to provide a simple, practical and efficient mechanism of this character, whereby the machine will be automatically stopped should the yarn become knotted or tangled, or when it is stretched too tight.

In the accompanying drawings: Figure 1 is a view in side elevation of a mechanism embodying my improvements detached from the machine; Fig. 2 is a rear elevation; Fig. 3 is a plan view of the supporting arm for the yieldable guides; Fig. 4 is a horizontal section taken on the line 4—4 of Fig. 1; Fig. 5 is a similar view taken on line 5—5 of Fig. 1, and, Figs. 6, 7 and 8 are detail perspective views of certain parts of the device.

Referring to the drawings for a more particular description of the invention the numeral 1 indicates a controlling device by means of which the machine may be stopped. 40 This device comprises a horizontally disposed shifting rod 2 arranged to work through guide members 3, preferably in the form of lugs rising from the upper face of an arm 4, constituting part of a horizontal bracket 5, adjustably secured to the frame or supporting member of the stop mechanism. The outer end of said shifting rod may be connected with the belt shifter of the machine in any suitable manner (not shown).

50 The improved stop mechanism 6 is supported from the machine by a horizontal bracket 7. Extending vertically through an opening in the bracket 7 and adjustable

vertically therein by a set screw 8, or other equivalent means is an upright supporting member, 9, which has fixed upon its lower end a cross-head 10, on which the yarn bobbins, 11, are mounted.

Fixed upon the upright supporting member, 9, is a cross-bar or yoke 12 having in its ends longitudinal recesses or slots 13, to receive the yarn and to serve as detectors for knots, slugs, motes and other abnormal enlargements in the yarn. This cross-bar or yoke is secured to or formed upon a block 14 or head, through which the supporting member, 9, extends. Hinged to the arms of the yoke, as at 15, are tripping devices, 16, which are held normally in an inoperative position by the yarn, and which, should the yarn break, will fall by gravity and disengage a latch device, 17, from a drop weight, 18, which latter in turn will descend and actuate a lever, 19, pivoted intermediately of its ends on the horizontal bracket, 5. The free end of this lever is adapted to be engaged normally in a notch 20 formed in the inner end of the shifting rod, 2, when said rod is set. This rod is provided with a coil or other actuating spring, 21, so that when 80 the free end of the lever is disengaged from its inner end the spring will effect endwise movement thereof and stop the machine.

Each of the trip devices, as shown, is formed from a single piece of wire or other 85 suitable material and comprises a straight horizontal portion 23 which is hinged to one of the arms of the yoke 12, is bent at right angles at its inner end to form a curved trip finger 24. The opposite end of said device 90 is bent at right angles to form an arm 25, which is bent alternately and laterally in opposite directions at its free end to form a plurality of straight substantially parallel bars or fingers 26, the purpose of which will be 95 disclosed.

A horizontal disposed guide member, 27, is fixed to the support or upright above the trip devices and is provided at each end with a plurality of vertically spaced inwardly projecting guide hooks or fingers 28 between which are adapted to be received the parallel bars or fingers, 26, of the trip devices, 16. A horizontally disposed support, 29, is also arranged above the guide members and has 105 pivoted to its ends horizontally disposed guide

members, 30, preferably in the form of wires bent or coiled near their free ends to form eyes 31 to receive the yarn.

In practice, the yarn is passed upward in 5 the longitudinal slots or recesses, 13, in the cross-bar or yoke, 12, thence through the guide hooks or fingers, 28, of the guide members 27, holding the arms of the trip devices, 16, in an inoperative position, but should the 10 yarn break and the trip devices be thereby released, they will be caused to fall by gravity and their fingers strike the outwardly bent ends of projections, 32, of the latch. The latter is in the form of a substantially U-shaped plate, 33, the parallel arms, 34, of which are pivoted as at, 35, to opposite sides of the block or head 14. The connecting portion, 36, of the U-shaped plate is adapted to have its inner edge seat in an annular 20 notch, 37, formed in the drop weight, so as to hold the latter in an elevated position. The drop weight is here shown in the form of a cylindrical rod mounted to slide in alining openings or apertures in the block or head, 25 14, and through corresponding apertures in the head of the horizontal guide, 27, and so as to strike or engage the pivot end of the lever, 19, when the latch is disengaged from its notch. The inner or pivot end of this lever 30 is preferably flattened.

Arranged upon the upright supporting member, 9, at or near the upper end thereof is a horizontally disposed arm, 38, which has mounted upon its free end two yieldable 35 guides, 39. These guides are here shown in the form of hooks pivoted upon screws, 40, and between friction washers, 41. Tension springs, 42, are arranged between the heads of the screws and the outermost washers, so 40 as to force the latter against the hooks or supporting elements and thus hold them in their normal horizontal positions.

A tension actuated trip device, 43, is arranged to slide longitudinally of the upright 45 supporting member, 9, and to trip the latch device, 17, so as to stop the machine, should the yarn become under abnormal tension. This device comprises an upright rod or member, 44, bent at its upper end to form a horizontally disposed projecting head or portion, 45, and a depending leg or portion, 46. This device also comprises a lower upright member, 47, which is adjustably connected with the lower end of the upright rod or member, 50 44, in any suitable manner and is bent upwardly at a suitable angle at its lower end to form an upwardly extending obliquely disposed trip finger 48 to engage the latch. Yieldable arms, 49, are pivoted at their inner 55 ends to the inner end of the horizontally disposed arm, 38, and are disposed approximately at right angles therewith. These arms are held in yieldable position in the same manner as the yieldable guides 39, and

are provided at their pivot ends with cams 65 50 adapted to engage the projecting head or portion, 45, of the tension actuated trip device, 43, when swung outward by an abnormal tension being exerted on the yarn, raising said trip device and tripping the latch. 70

The operation of my invention is as follows: The yarn passes from the bobbins, 11, forwardly through the detectors, thence upwardly through the guide hooks or fingers, 28, of the guide member, 27, thence through 75 the eyes, 31, of the guide, 30, and thence over the free end of the yieldable arm and fingers, 49, and 39, respectively to the machine. The yarn in passing from the detectors through the machine travels in an angular 80 direction, and when a knot, tangle or other enlargement upon the yarn reaches the detectors, that portion of the yarn between the latter and the machine becomes stretched and causes the yieldable guides and arms, 39 85 and 49, respectively to swing outwardly, the cams at the pivot ends of the arms engaging the projecting head or portion of the upper upright rod or member of the trip device, 43, causing said device to trip the latch and release the drop weight. When the drop weight is released it strikes the pivot end of the lever, 19, and releases the free end thereof from engagement with the rod or member, 2, 90 when the latter is caused to move endwise 95 a predetermined distance by its actuating spring, and stop the machine. The trip devices, 16, are normally held in inoperative position by the yarn but should the latter break, they will be released and trip the 100 latch.

Having thus described my invention, what I claim as new and desire to secure by Letters-Patent, is:

1. A stop - motion for textile machines, 105 comprising an upright support, a controller to stop the machine, a releasing lever for the controller, a knot catcher, a drop weight to operate the lever, a latch to normally support the weight in an elevated position, an 110 upright longitudinally movable trip device carried by the support, said device having a horizontally projecting portion at its upper end, and yieldable yarn guiding arms pivoted to the support, said arms having cams at 115 their pivot ends to engage the projecting portion of the trip device when swung upward by an abnormal tension being exerted on the arm.

2. A stop motion for knitting machines 120 comprising an upright support, a controller to stop the machine, a drop weight to release the controller, a latch device to support the weight, an upright longitudinally movable trip device sustained by the support, said 125 device having a horizontally projecting portion at its upper end, and an upwardly extending trip finger at its lower end, the latter

of which is adapted to engage the latch device, and yieldable yarn guiding arms pivoted to the support, said arms having cams at their pivot ends to engage with the projecting portion of said trip device to raise the latter when said arms are swung downwardly by abnormal tension being exerted thereon.

In testimony whereof I have hereunto set my hand in presence of two subscribing witnesses.

JOSEPH B. RHODES.
